UNITED STATES PATENT OFFICE.

EARL SHEELEY, OF PHILADELPHIA, PENNSYLVANIA, ASSIGNOR TO WRIGHT MANUFACTURING COMPANY, INC., OF PHILADELPHIA, PENNSYLVANIA, A CORPORATION OF PENNSYLVANIA.

DESIGN FOR A VIGIL LIGHT CUP.

Application filed May 8, 1928. Serial No. 26,609. Term of patent 14 years.

To all whom it may concern:

Be it known that I, EARL SHEELEY, a citizen of the United States, residing at Philadelphia, in the county of Philadelphia and State of Pennsylvania, have invented a new, original, and ornamental Design for a Vigil Light Cup, of which the following is a specification, reference being had to the accompanying drawing, forming a part thereof.

The figure is a perspective view of a vigil light cup, showing my new design.

I claim:

The ornamental design for a vigil light cup, as shown.

EARL SHEELEY.
